[57] CLAIM

The ornamental design for a handle, as shown and described.

DESCRIPTION

FIG. 1 is a perspective view of a handle showing my new design;

FIG. 2 is a top plan view thereof;

FIG. 3 is a rear elevational view thereof;

FIG. 4 is a bottom view thereof;

FIG. 5 is a front elevational view thereof; and,

FIG. 6 is a side elevational view thereof.

The broken lines in FIG. 3 and 4 represent the bounds of the claimed design but form no part thereof.
